UNITED STATES PATENT OFFICE.

THOMAS W. VANBUSKIRK, OF JUNIATA, PENNSYLVANIA, ASSIGNOR OF ONE-HALF TO
JOHN L. BRUBAKER, OF JUNIATA, PENNSYLVANIA.

TRAIN-STOPPING DEVICE.

1,184,279.

Specification of Letters Patent.

Patented May 23, 1916.

Application filed October 31, 1913, Serial No. 798,564. Renewed March 30, 1916. Serial No. 87,847.

To all whom it may concern:

Be it known that I, THOMAS W. VANBUSKIRK, a citizen of the United States, residing at Juniata, in the county of Blair 5 and State of Pennsylvania, have invented certain new and useful Improvements in Train-Stopping Devices, of which the following is a specification.

This invention relates to an improved 10 train-stopping device, and the principal object of the invention is to provide a device which will cause a train to stop in case the engineer runs past a set signal.

Another object of the invention is to so 15 construct the train-engaging device which is mounted upon a semaphore pole that it will be moved to a set position when the semaphore arm is set to stop a train.

Another object of the invention is to provide 20 an improved train device which will operate the throttle controlling the air pipe and after passing the signal will leave the throttle in the adjusted position so that it may be returned to its original position by 25 the engineer.

This invention is illustrated in the accompanying drawings wherein—

Figure 1 is a view showing the signal set 30 to stop a train and the train device about to engage the contact arm carried by the pole; Fig. 2 is a top-plan view with the roof of the cab broken away and the pole shown in section along the line 2—2 of Fig. 1; Fig. 3 is a view similar to Fig. 1, but 35 shows a modified construction.

The air pipe 10 enters the cab 11 and is provided with a control throttle 12 so that the engineer can apply the air brakes when necessary. A lever 13 is pivotally mounted 40 upon the top of the cab and is connected with the throttle 12 by means of the flexible connection 14 which may be a chain as shown in Fig. 1, or a cable as shown in Fig. 3. It should also be noted that the lever 13 45 may extend vertically as shown in Fig. 1, or horizontally as shown in Fig. 3. The device for operating the lever 13 is pivotally mounted upon the semaphore pole 15 beneath the semaphore arm 16 and is connected with the semaphore arm by means of a rod 17 so that the operating device will move 50 simultaneously with the semaphore arm.

The operating device shown in Figs. 1 and 2 comprises an arcuate-body portion 55 18 which is braced by the longitudinally ex-

tending bars 19 and cross bars 20 and 21. The longitudinally extending bars 19 are carried beyond the cross bars 21 to form arms 22 which are pivotally connected with the pole 15 by means of the bolt 23. This 60 operating device is formed arcuate so that when the lever 13 hits the operating device, the lever will not receive a violent blow which would be liable to break the lever or the flexible connection, but strikes the operating device with a glancing blow which causes the lever to swing upon its pivots and draw the flexible connection to move the throttle 12 and permit the air to operate the air brakes.

The operating device 24 which is used in the form shown in Fig. 3 is pivotally connected with the pole by means of the bolt 25 and has its outer end provided with an arm 26 which extends vertically when the signal 75 is in a set position and thus prevents any danger of the lever missing the operating device when passing the signal.

The operation of this device is as follows: When the station master wishes the train to 80 stop at his station, he sets the semaphore arm and this causes the operating device to extend horizontally as shown in Figs. 1 and 3.

When the train approaches the station, the engineer is supposed to see the set signal 85 and stop the train, but it very often happens that on a foggy night the engineer cannot see the signal and runs past the station. This will be impossible when the train is applied with this safety device since the 90 lever 13 will strike the operating device carried by the semaphore pole and this will cause the throttle to be opened so that the air brakes can be operated. The train will then be brought to a stop and the engineer 95

must then manually operate the throttle 12 before the train can be again started. It will thus be seen that a device has been provided which will make it impossible for a train to pass a set signal without stopping, and it will also be seen that a device of this 100 character has been provided which is very simple in construction and which will operate very efficiently since there is no danger of the lever or flexible connection being broken when striking the operating device.

What is claimed is:

In a train stop of the character described a station device comprising a support, an operating device carried by said support, 110

said operating device comprising an arcuate body portion, longitudinally extending bracing bars for said body portion, cross bars extending from said longitudinally extending bars to said body portion, said longitudinally extending bars being carried to form pivot arms positioned upon opposite sides of said support, means passing through said support and engaging said arms to pivotally mount said operating device, a signal car-

ried by said support, and means connecting said signal with said operating device for causing said operating device to be moved to a set position with said signal.

In testimony whereof I affix my signature 13
in presence of two witnesses.

THOS. W. VANBUSKIRK.
